[57] CLAIM

The ornamental design for a lavatory or similar article, substantially as shown and described.

DESCRIPTION

FIG. 1 is a front elevational view of a lavatory embodying my new design;

FIG. 2 is a right side elevational view thereof, the left side being a mirror image of the right side shown;

FIG. 3 is a top plan view thereof;

FIG. 4 is a rear elevational view thereof;

FIG. 5 is a bottom plan view thereof;

FIG. 6 is a cross sectional view taken on line 6—6 of

FIG. 3; and

FIG. 7 is a cross sectional view taken on line 7—7 of FIG. 3.
